(57) **CLAIM**

The ornamental design for a rope assembly, as shown and described.

DESCRIPTION

FIG. 1 is a top perspective view of a rope assembly showing our new design;

FIG. 2 is a front view thereof, the back view being the same image thereof;

FIG. 3 is a top view thereof, the bottom view being the mirror image thereof;

FIG. 4 is a right side view thereof;

FIG. 5 is a left side view thereof;

FIG. 6 is a top perspective view of a second embodiment of a rope assembly showing our new design;

FIG. 7 is a front view thereof, the back view being the same image thereof;

FIG. 8 is a top view thereof, the bottom view being the mirror image thereof;

FIG. 9 is a right side view thereof;

FIG. 10 is a left side view thereof;

FIG. 11 is a top perspective view of a third embodiment of a rope assembly showing our new design;

FIG. 12 is a front view thereof, the back view being the same image thereof;

FIG. 13 is a top view thereof, the bottom view being the mirror image thereof;

FIG. 14 is a right side view thereof; and,

FIG. 15 is a left side view thereof.
